[57] CLAIM

The ornamental design for the container for a food product, as shown and described.

DESCRIPTION

FIG. 1 is a front elevational view of the container for a food product showing my new design; each of the rear, right side and left side elevational views being a mirror image to the front elevational view;

FIG. 2 is a top view thereof, the bottom plan view appearing the same as the top plan view;

FIG. 3 is a perspective view taken from the top, front and right side of the container; and,

FIG. 4 is a central vertical cross sectional view of the container shown in FIG. 1.
